UNITED STATES PATENT OFFICE.

EDWARD J. BRANDT, OF WATERTOWN, WISCONSIN, ASSIGNOR TO BRANDT CASHIER COMPANY, OF CHICAGO, ILLINOIS, A CORPORATION OF ILLINOIS.

CHANGE-MAKER.

1,266,098.

Specification of Letters Patent. Patented May 14, 1918.

Application filed April 10, 1916. Serial No. 90,213.

To all whom it may concern:

Be it known that I, EDWARD J. BRANDT, a citizen of the United States, and resident of Watertown, in the county of Jefferson and State of Wisconsin, have invented certain new and useful Improvements in Change-Makers, of which the following is a specification.

My invention relates to change making devices and has particular reference to novel 10 ejector actuating mechanism for use in connection with change-making machines.

The invention is illustrated in connection with a simple change-making machine providing for the accommodation of coin of the denominations of one-half dollar, one-quarter dollar, dime, nickel and cent.

An object of the invention is to provide 20 a mechanism adapted to be operated solely by the sense of touch, the coin-operating levers corresponding in number to the fingers and thumb of the operator's hand; that is to say, each denomination of coins is controlled by one finger or thumb of the hand. There 25 being five denominations of coins which are delivered by the machine, I have provided means whereby the thumb actuates a lever which pays or delivers pennies, the index finger causes the delivery of nickels, the 30 middle finger delivers dimes, the third finger delivers quarters and the fourth finger delivers halves. The arrangement is such that the hand fits within a space and the fingers are disposed opposite the corresponding 35 lever or key which that finger is intended to actuate. By the use of this means the operator may deliver change very rapidly and accurately without the necessity for visual attention. Furthermore, as a matter

40 of convenience, I have arranged a mechanism whereby the fingers exert a pull in order to actuate corresponding levers or keys, while the thumb exerts a pressure in an opposite direction, this being according 45 to the natural position of the hand. If desired, of course, the arrangement shown may be reversed, that is—the thumb may deliver half dollars, the index finger quarters, etc. The broad idea is in the digit 50 control, each finger and the thumb of the hand being supplied with a lever, each finger always paying the same coin.

The invention will be more readily un-

derstood by reference to the accompanying drawings, wherein—

55 Figure 1 is an elevation of a machine to which my invention has been applied;

Fig. 2 is a sectional view on the line 2—2 of Fig. 3;

Fig. 3 is a sectional view on the line 3—3 of Fig. 4, and

Fig. 4 is a sectional view on the line 4—4 of Fig. 3.

Referring more particularly to the drawings, it will be seen that the coin tray provides for the accommodation of half dollars in the space 10, quarters in the space 11, dimes in the space 12, nickels in the space 13 and pennies in the space 14. A casing 15 serves as a support for the coin tray. Secured to the casing is a hopper having converging side walls 16 terminating in an outlet or chute 17, beneath which the palm of the operator's hand is located while in the operating position.

75 Mounted on a horizontal shaft 18 within the casing 15 are a plurality of pendant ejector supports 19, one of these supports being provided for each denomination of coins. The members 19 are held in normally 80 retracted position by means of a coil spring 20 acting upon a ball 21, which presses the upper end of the lever. The lower end of the ejector support 19 is deflected laterally to form a foot 22, the lower edge 23 of which 85 is curved to form a cam coöperating with the finger lever 24, pivoted at 25, and having a downwardly projecting end portion 26. The curved terminal portion of the end 26 is intended to be contacted by the 90 finger of the operator and by an upward movement to transmit motion to the ejector support 19. The coin ejectors 27 are pivoted to the ejector supports at 28 and are normally held in raised position by means of 95 the coil spring 29. The ejectors extend through openings 30 at the lower end of the coin receiving space and operate in a well-known manner.

100 The preceding description applies to the finger-operated mechanism. The thumb-operated mechanism is best shown in Fig. 4. The ejector support 31 is the same as that previously described, except in that it has no cam at its lower end. Motion is imparted to the ejector support by means of a lever

- 32, pivoted at 33, the outer end 34 of which is adapted to be contacted by the thumb of the operator. The lever 32 is in the form of a bell crank, one arm 35 of which bears 5 against a projection 36 on the ejector support 31. The ejector 37 is pivoted to and operates in the same manner as described in connection with the construction shown in Fig. 2. A downward pressure on the point 10 34 of the operating lever serves to eject the coins controlled by the thumb levers in distinction from an upward pressure necessary to operate the levers controlled by the fingers, as previously described.
- 15 In order that the hand of the operator may be caused to be positioned properly with the fingers opposite the proper keys, I provide curved guides 38, 39, which are secured to the frame or casing one at each side 20 of the opening in the front lower portion thereof. These are so spaced as to permit the ready insertion of the operator's hand, but without sufficient space to allow for such position that the fingers of the hand might 25 come in contact with other than the proper levers. It will be found that the thumb will naturally occupy a space contiguous to the lever 34, which is in the proper position for operating the levers.
- 30 It will be noted that the total space occupied by the five keys is somewhat less than the total transverse space occupied by the stack of coins. This is necessary if the hand of the operator is to be positioned for 35 natural actuation of the levers by the fingers. The ordinary operator has not sufficient span to engage the keys if they were not spaced differently from the spacing of the coin stacks.
- 40 It will further be noted that the thumb operated ejector key is offset with relation to the guide 38, the guides 38, 39, being positioned to engage the sides of the palm of the operator's hand, the thumb key lying in 45 front of the guide in position to be readily engaged by the thumb.
- By the use of the mechanism here described, an operator may become expert in the paying of coins with a little practice, 50 all the operations being carried out without necessity for looking at the machine. The machine is practically a hand extension requiring no view of the keys, as the machine is designed for the shape of the hand and fingers.
- 55 The construction is capable of considerable modification and such modifications as are within the scope of my claims I consider within the spirit of my invention.
- 60 I claim:
1. In a coin-delivering device, the combination of means for supporting a plurality of stacks of coins of different denominations, a hopper disposed at the base of said 65 stacks and having a restricted outlet open-

ing; an ejector for each stack of coins; four finger levers and one thumb lever connected to said ejectors and side guides so disposed as to cause the hand of an operator to assume a position in which the fingers of the 70 hand register with four of said levers and in such position that the palm of the hand will be beneath the outlet opening in said hopper, substantially as described.

2. In a device of the class described, the 75 combination of a casing providing an opening in the lower forward portion thereof, means on said casing for supporting a plurality of stacks of coins, ejectors mounted in said casing, five levers controlling the actuation of said ejectors, said levers being disposed in said opening; and guides mounted at the sides of said opening whereby the hand of the operator is caused to assume a position in which the fingers and thumb 80 register with said levers, substantially as described.

3. In a coin delivering device, the combination of means for supporting a plurality of stacks of coins of different denominations, a hopper disposed at the base of said 90 stacks, said hopper being provided with a restricted outlet near the transverse center of the device; ejectors for the coins, levers for operating said ejectors, a number of levers 95 being employed corresponding to the fingers and thumb of the hand; said levers being so positioned as to occupy a space less than the width of the juxtaposed stacks of coins, and guide members located adjacent to the extreme levers, said guide members acting to direct and confine the hand in a predetermined position, substantially as described.

4. In a coin delivering device, the combination of a casing providing for stacks of 105 coins, a hopper for causing ejected coins to be delivered at a central outlet, key-operated ejectors for said coins, four of the keys being spaced in accordance with the position of the four fingers of the hand, a guide 110 at each side of the four keys, said guide being adapted to engage the sides of the palm of the hand, and a fifth key adapted for actuation by the thumb, said key being offset with relation to said guides and being positioned in such manner as to be naturally engaged by the thumb, substantially as described.

5. In a coin delivering device, the combination of a casing providing for stacks of 120 coins, a hopper for causing ejected coins to be delivered at a central outlet, key-operated ejectors for said coins, four of the keys being spaced in accordance with the position of the four fingers of the hand, a guide 125 at each side of the four keys, said guide being adapted to engage the sides of the palm of the hand, and a fifth key adapted for actuation by the thumb, said key being offset with relation to said guides and being po- 130

5 sitioned in such manner as to be naturally engaged by the thumb, the space within which the keys are mounted being materially less than the width of the stacks and being such as to correspond to the reach of an operator's hand, substantially as described.

10 6. In a device for delivering coins, the combination of a casing providing a plurality of adjacent holders for coins, ejectors for the coins, keys for operating the ejectors, a hopper for causing the ejected coins to be delivered at a central outlet, five keys being employed, a guide for each side of the 15 palm of the hand of the operator, said guides being located at the sides of four of

said keys whereby the hand of the operator with the palm upward is directed into such positions that the fingers are in proper position to engage said keys and to actuate the 20 same by an upward movement of the fingers, the fifth lever being located at one side of the guide and in such position as to be contacted by the thumb and actuated by a natural downward movement thereof, substantially as described.

Signed at Chicago, Illinois, this 7th day of April, A. D. 1916.

EDWARD J. BRANDT.
